UNITED STATES PATENT OFFICE

157,369

HAT

Elizabeth N. Graham, New York, N. Y.

Application June 9, 1949, Serial No. 3,149

Term of patent 7 years

(Cl. D3—13)

To all whom it may concern:

Be it known that I, Elizabeth N. Graham, a citizen of the United States of America, residing in New York city, county of New York, and State of New York, have invented a new, original, and ornamental Design for a Hat, of which the following is a specification, reference being had to the accompanying drawing, forming part thereof, wherein,

The opposite side of the hat is identical in appearance to the side shown in Figure 3.

I claim:

The ornamental design for a hat, substantially as shown and described.

ELIZABETH N. GRAHAM.
